INVENTOR
A. POLI,
BY *Adam E. Fisher*,
ATTORNEY

UNITED STATES PATENT OFFICE.

ALPHERIA POLI, OF WALSENBURG, COLORADO.

CIGARETTE-MAKING DEVICE.

1,304,598.

Specification of Letters Patent. Patented May 27, 1919.

Application filed March 8, 1919. Serial No. 281,453.

To all whom it may concern:

Be it known that I, ALPHERIA POLI, a citizen of the United States, residing in the city of Walsenburg and State of Colorado, have invented new and useful Improvements in Cigarette-Making Devices, of which the following is a specification, reference being had to the accompanying drawings.

10 This invention pertains to cigarette making devices and the object of the invention is to produce a simple, practical and efficient device, which may be easily carried in the vest pocket and with which tobacco cigarettes may be rapidly made by a smoker as he requires same in use.

With this object in view, attention is called to the accompanying drawings constituting a part of this specification, wherein:

20 Figure 1 is a perspective view showing one of the devices as used for making cigarettes;

Fig. 2 is a sectional, side elevation showing a part of the tube and part of the hopper cut away so as to reveal the action of the plunger;

Fig. 3 is a top plan view;

Fig. 4 is a bottom end view showing the corrugated construction of the tube.

30 Fig. 5 is a detail showing a method of forming a lock at the upper end of the wire plunger by bending the wire forwardly, then down and backwardly and slightly to one side.

35 In carrying out my invention in its preferred construction, I provide a corrugated tube (1) of a suitable diameter for forming standard cigarettes. This tube (1) is corrugated longitudinally as shown at (2) to lessen friction and so as to enable the cigarette wrapper (3), wrapped about the same, to be readily withdrawn from the tube (1) in the process of making the cigarette (4).

40 At the upper end of the tube (1) is rigidly attached a flattened, funnel-like hopper (5), the spread of the hopper being extended almost entirely toward the one side (6) leaving the other side (7) almost in alignment with the walls of the tube (1).

45 A lobe (8) is extended from the side (7) of the hopper (5) inwardly over the bore (9) of the tube (1) and a small plunger guide-hole (10) is pierced through this lobe (8). Through the plunger guide-hole (10) is 55 slidingly mounted a wire plunger (11), said plunger being bent at the upper end to form

a suitable handle (12) and being twisted or gnarled at its lower end to form the shoe (13) adapted to engage the tobacco (14) as same is fed into the wrapper (3) during the process of making a cigarette. The handle (12) is preferably completed by bending the wire first forwardly at right angles to the plunger (11), then down and back upon itself, after which the extreme end (15) is bent slightly to one side, thus forming an opening (16) adapted to receive the lobe (8) edgewise by twisting or turning said plunger, so as to lock the plunger (11) down into the tube (1) when the device is not in use.

In operation the cigarette paper is wrapped around outside the tube (1) and is sealed in place, thus forming the wrapper (3). The tobacco (14) is then poured into the hopper (5). The thumb is then placed over the lower end of the tube (1) and the plunger (11) is operated, thereby feeding the tobacco down into the tube (1) and compressing same. At the same time the wrapper (3) is slowly withdrawn from the metal tube (1), the tobacco being simultaneously fed on down into the said wrapper and compressed into place by means of the plunger (11). When the wrapper is entirely filled and withdrawn from the metal tube (1), the cigarette (4) is complete. It will be noted that the corrugated formation of the tube (1) enables the wrapper to be easily withdrawn from the metal tube, inasmuch as there is very slight friction between the two. This device is simple in construction as it can be stamped from a single piece of sheet metal. It is light and easy to carry about and makes cigarettes quickly and of compact form and neat shape.

While I have herein described a certain specific method of constructing and assembling the elements of my invention, it is understood same may be varied in minor details, not departing from the spirit of my invention as defined in the appended claim.

What I claim to be new and patentable is:

A cigarette making device, comprising a feed tube for feeding tobacco into the cigarette wrapper; a feed-hopper mounted at the top of said feed-tube as means for feeding tobacco through said tube; a lobe extended from the upper edge of the feed-hopper inwardly over the bore of the feed-tube, said lobe being pierced with a plun-

ger guide-hole; a wire plunger slidingly mounted through said guide-hole in said lobe, and ending in a handle at its upper end and in a shoe at its lower end, as means for feeding and pressing tobacco through said tube into the cigarette wrapper, said handle being formed by bending the wire for-

wardly, then down, back and to one side, so as to form a lock for engaging the lobe aforesaid.

ALPHERIA POLI.
